Primary Examiner—Brian N. Vinson

[57] **CLAIM**

The ornamental design for a "clear data from a batch queue" icon for a display screen of a programmed computer system, as shown and described.

DESCRIPTION

The single FIGURE is an elevational view of a "clear data from a batch cue" icon for a display screen of a programmed computer system showing my new design, the broken-line disclosure of the portion of the screen being for illustrative purposes only and forming no part of the claimed design.
